UNITED STATES PATENT OFFICE.

JOHN GILSON, OF PORT WASHINGTON, WISCONSIN.

CHAIR.

No. 824,714.

Specification of Letters Patent.

Patented July 3, 1906.

Application filed February 6, 1905. Serial No. 244,282.

To all whom it may concern:

Be it known that I, JOHN GILSON, a citizen of the United States, and a resident of Port Washington, in the county of Ozaukee and 5 State of Wisconsin, have invented certain new and useful Improvements in Chairs; and I do hereby declare that the following is a full, clear, and exact description thereof.

My invention consists in certain peculiarities of construction and combination of parts, hereinafter described with reference to the accompanying drawings and subsequently claimed, its object being to provide 10 simple, economical, light, strong, and durable seat-spiders for tilting chairs.

Figure 1 of the drawings represents a vertical longitudinal section view of a chair-seat spider in accordance with my invention; Fig. 2, a plan view of the spider inverted and 20 partly in horizontal section; Fig. 3, a transverse sectional view of said spider, this view being indicated by lines 3 3 in Fig. 1; Fig. 4, a similar view on the plane indicated by line 4 4 in Fig. 2, and Fig. 5 a perspective view of 25 one of a pair of pivot-brackets in the spider.

Referring by letter to the drawings, A indicates a standard having a hub b, in which the upper end of a seat-spider pivot (not shown) is made fast, and to this standard the 30 depending ears c of my improved seat-spider are pivotally connected by a rod B, as is common in the art. The usual upwardly-projecting stop-lugs d are provided on the standard.

35 Each spider-ear c is a depending portion of an angular bracket C, that constitutes an arch, and results from suitable bending of what is preferably a sheet-steel blank. Riveted or otherwise suitably connected to upper 40 horizontal portions of the opposite brackets is a bridge-plate D and right-angle spider-arms E, these arms being preferably made from sheet-steel bent into the angular form shown and arranged to overlap the bridge-plate. 45 The vertical upper portions of the brackets are bent to provide outer lateral flanges e forward of the pivot-ear c, and the vertical portion of an arm E rests on said flanges. Each arch-bracket of the pair has the inner 50 wall thereof horizontally extended and provided with an inner recess, the extensions of said wall being ears f, and the stop-lugs d of the standard A engage the recesses of the brackets. Forward tilt of a chair-seat is limited by contact of the rear ears of the 55 brackets with the stop-lugs of the standard,

and rearward tilt of said seat is limited by contact of the front ears of said brackets with said lugs. The central portion of the seat-spider is of minimum width, and said 60 bars are bent at the front and rear to increase the distance between the same and to provide for greater rigidity of connection with a chair-seat frame. It is within the scope of my invention to make the ears f continuous between the brackets and omit the bridge-plate. The channel-arms E of the spider may be otherwise than right angular in cross-section. 65

The bridge-plate D is set in on lower lugs 70 g of a rear brace-bar F between the spider-arms, and an upper lug h of the brace-bar overlaps said plate central of the same. Other lugs g' of the brace-bar rest on the ears f of the pivot-brackets. The brace-bar 75 is provided with rear bosses i, that engage ends of spiral springs G, that are also supported at their other ends on bosses j of a tension-bar H on a rod I, that extends through a forward central recess of the 80 standard. The sustaining-sleeve J on the rod I is provided with the usual lateral lugs k in rocking engagement with notches in parallel ribs m of the standard, and the nut K, running on the screw-threaded end of said 85 rod against said sleeve, serves to regulate the tension of the springs aforesaid.

Having thus described my invention, what I claim as new, and desire to secure by Letters Patent, is— 90

1. A chair-seat spider comprising a pair of opposite brackets each constituting an arch having the inner wall thereof vertically recessed and horizontally extended adjacent to the recess to form ears, a standard provided 95 with lugs engaging the inner-wall recesses of the brackets, a bridge-plate fastened at its ends on said brackets, and arms in rigid connection with the plate and brackets.

2. A chair-seat spider comprising a pair of 100 opposite brackets each constituting an arch provided with outer lateral flanges and inner horizontal ears, a standard provided with stop-lugs each engaging space between the aforesaid ears of a bracket, a bridge-plate on the brackets, arms supported on the bridge-plate and outer flanges of the brackets, and means rigidly connecting the arms, bridge-plate and brackets. 105

3. A chair-seat spider comprising a pair of 110 opposite arch-brackets each having a depending pivot-ear and horizontal inner ears, a

standard to which the pivot-ears of the bracket are connected and which is provided with stop-lugs each of which engages space between said horizontal inner ears of a bracket, a bridge-plate on the brackets, arms on the bridge-plate, and means rigidly connecting the arms, bridge-plate and brackets.

4. A chair-seat spider comprising a pair of connected pivot-brackets each constituting an arch having the inner wall thereof vertically recessed to provide a play-space for the engagement of a stop-lug of a standard to which the spider is pivotally connected.

5. A chair-seat spider comprising a pair of connected brackets each constituting an arch having the inner wall thereof provided with play-space for the engagement of a stop-lug of a standard to which the spider is pivotally connected, arms in rigid connection with the brackets, and a spring-supporting brace-bar between the arms.

6. A chair-seat spider comprising a pair of connected brackets each constituting an arch having the inner wall thereof provided with horizontal extensions and recessed to provide limited play-space for a stop-lug of a standard to which the spider is pivotally connected, a bridge-plate on the brackets, arms in rigid connection with said brackets and interposed bridge-plate, and a spring-supporting brace-bar between the arms provided with lugs that lap opposite sides of the bridge-plate and rest on inner-wall extensions of the aforesaid brackets.

In testimony that I claim the foregoing I have hereunto set my hand, at Port Washington, in the county of Ozaukee and State of Wisconsin, in the presence of two witnesses.

JOHN GILSON.
